CLAIM

The ornamental design for a hand mitten, as shown and described.

DESCRIPTION

FIG. 1 is an upper perspective view of a hand mitten of my new design having a flap portion thereof opened to permit inspection of the hand and fingers of a patient; and, FIG. 2 is another view thereof with the flap closed.

The broken lines in the drawings, except those broken lines depicting a hand, illustrate portions of the article and form no part of the claimed design. The broken lines depicting a hand illustrate environment and form no part of the claimed design.
